(57) **CLAIM**

The ornamental design for an array of transport elements for supporting and moving plant pots, as shown and described.

DESCRIPTION

FIG. 1 is a top view of the array of transport elements for supporting and moving plant pots showing our new design,

FIG. 2 is an enlarged left lower corner view thereof;

FIG. 3 is an enlarged right lower corner view thereof;

FIG. 4 is an enlarged upper left corner view thereof;

FIG. 5 is an enlarged upper right corner view thereof; and,

FIG. 6 is a perspective view of one of the transport element of our design, a portion of the unclaimed wall has been removed for clarity of illustration.

The broken line dividing the array of transport elements in four sections in FIG. 1 and the additional figure legends are included to clearly identify the areas shown in enlarged FIGS. 2 through 5.

The broken lines in the figures are included for the purpose of illustrating environment and form no part of the claimed design.

1 Claim, 6 Drawing Sheets
